[57] CLAIM

The ornamental design for a latch, as shown.

DESCRIPTION

FIG. 1 is a perspective view of my latch;
FIG. 2 is an elevational view looking at the righthand
face of the latch as shown in FIG. 1;
FIG. 3 is an elevational view looking at the lefthand
side of the latch as viewed in FIG. 1;
FIG. 4 is a top view thereof;
FIG. 5 is a bottom view thereof;
FIG. 6 is an elevational view one side thereof; and
FIG. 7 is an elevational view of the opposite side
thereof.
